UNITED STATES PATENT OFFICE.

DANIEL M. McLAUGHLIN, OF LOUISVILLE, KENTUCKY.

VALVE.

1,359,187.

Specification of Letters Patent. Patented Nov. 16, 1920.

Application filed May 16, 1918. Serial No. 234,955.

To all whom it may concern:

Be it known that I, DANIEL M. McLAUGHLIN, a citizen of the United States, residing at Louisville, in the county of Jefferson and 5 State of Kentucky, have invented certain new Improvements in Valves; and I hereby declare the following to be a full, clear, and exact description of the invention, such as will enable others skilled in the art to which 10 it pertains to make and use the same.

My invention relates to a valve and has for its object to provide an economical form of valve adaptable for various kinds of service and comprising few parts which are 15 both simple in construction and in operation.

A further object of the invention is to provide a valve practically noiseless in operation which is particularly adapted for 20 use in connection with the flushing of closet bowls and one which is applicable to service pipes of different sizes.

Still another object of the invention is to provide an automatic valve with means for 25 effecting the gradual return of the valve to its seat when opened.

To these and other ends the invention consists in certain improvements and combinations of parts, all as will be hereinafter 30 more fully described, the novel features being pointed out in the claims at the end of the specification.

In the drawings:

Figure 1 is a side elevation of a valve embodying one form of the invention;

Fig. 2 is a sectional elevation through the valve showing the parts in normal position, and

Fig. 3 is a transverse sectional view taken 40 on line 2^a—2^a of Fig. 2.

Similar reference numerals in the several figures indicate the same parts.

In carrying out my present invention I have provided a liquid controlling valve 45 applicable for various branches of service in connection with the handling of liquids, but one which is especially adapted for use in connection with water closets where it is desired to economize in space and provide a 50 valve which may be conveniently located and operated for flushing a closet bowl (not shown).

A valve of the type which I have provided is adapted to be opened and closed by 55 the liquid in the service pipes which nor-

mally holds the valve seated and which is conveyed to one side thereof by means of a by-pass controlled by a small manually operated valve.

Referring now to the drawings, 10 represents a valve casing provided preferably with the upper and lower threaded inlet and outlet portions 11 and 12 by which said casing is connected with the service pipe and bowl or similar vessel (not shown), through 60 which the liquid is to be discharged. The casing is provided with the upper and lower screw caps 13 and 14 respectively, which serve as stops or limiting members for the valve and the actuating means there- 65 for. The valve proper, which is indicated at 15 and which is movable in the chamber 16, is normally held upon its seat 17 by the pressure of the liquid in said chamber which is at all times in communication with the 70 service or supply pipe 18, as shown in Fig. 3. The valve 15 is provided with a centrally disposed recess 19 into which loosely projects the reduced portion 20 of the piston stem 21 which is preferably integral with 80 the head 22 of the piston, to which is connected the flexible packing 23, held upon the head by means of the nut or clamping member 24 screwed into the recess 25 of said head, which normally remains in its 85 lowermost position within the cylindrical casing 10, as shown in Fig. 2. The stem of the piston is provided with a centrally disposed bore 26 extending therethrough and communicating with the recess 19 of the 90 valve 15 and at its lower end with the recess 25 of the piston.

Projecting loosely into the bore 26 is a tapering pin or member 27 threaded at its lower end and screwed into the centrally 95 disposed boss 28 of the head or cap 14 and held in the desired adjusted position by means of the locking nut 29 which serves as a stop to limit the downward movement of the piston by engaging the clamping nut 24 through which loosely extends the tapered pin, as shown in Fig. 2. The stem of the piston is provided with a shoulder or abutment 30 which when moved up engages the flange 31 connected with the valve 15 proper by the reduced portion 32 having the laterally extending ribs 33 serving to guide the valve in its up and down movement.

When the valve 15 is unseated, liquid will 110

flow from the chamber 16 into the outlet portion 12 of the casing and in doing so will strike the upper sloping surface of the flange 31 which serves to check the flow of the liquid and to spray or spread the same so that it will enter the bowl (not shown) with the least possible force, thereby reducing to a minimum the noise created by the liquid when discharged.

10 The valve when raised is limited in its upward movement by the extension 32^a which engages the boss 33^a of the screw cap 13.

15 At one side of the valve casing is a laterally disposed projection or member 34 upon which is mounted a stuffing box 35 carrying the gland 36 for retaining the packing 37 through which projects the reciprocally mounted rod 38 having on its upper 20 end the button 39 engaging the spring 40 within said gland, the rod carrying at its lower end a valve 41 normally held in engagement with its seat 42 by means of said spring, as shown in Fig. 2.

25 By pressing down upon the button 39, the valve 41 is moved from its seat into a pocket or recess 43 which communicates with the supply pipe 18 through the by-pass 44, as shown in Fig. 3. When the valve 41 is 30 open the pocket 43 and by-pass 44 are placed in communication with the transverse opening 45 through the bottom of the stuffing box, said opening leading to the vertically disposed passageway 46 which extends to 35 the bottom of the casing 10 and communicates with the same through the port 47 in the wall of the casing at a point to deliver beneath the piston the liquid from the supply pipe for the purpose of raising said 40 piston to elevate the valve 15.

When the valve has been raised from its seat by the action of the liquid admitted from the service pipe through the passageway 46 to the bottom of the piston in the lower end of the valve casing and the valve 41 closed, the pressure of the liquid in the chamber 16 will again close the valve 15. In doing so, however, said valve will be gradually returned to its normal position by reason of the cushioning effect produced by the liquid which accumulates in the recess 19 and enters and escapes through the bore 26 of the piston stem around the tapering pin 27 into the recess 25 and thence 50 through the central opening of the packing nut 24 which is only slightly larger in diameter than the greatest diameter of the pin. When the piston is in its highest position a very small amount of the upper extremity of the pin will project into the bore 26 and at this time, of course, the size of the liquid outlet around the pin is at its maximum, and it is the gradual decrease in the size of this opening as the piston 55 moves down that more and more restricts

the escape of the liquid which retards the downward movement of the valve and permits it to be seated gradually and without producing the hammering or clicking sounds common to valves of this kind.

70 The pin 27 is adjustable, as shown in Fig. 2, for the purpose of increasing or decreasing, as desired, the size of the liquid outlet opening through the piston stem and packing nut and is held in adjusted position by the lock nut 29, as previously stated.

75 In order to protect the valve 15 against undue action of the liquid entering the chamber 16 from the supply pipe 18 and tending to unseat said valve by striking the same on one side thereof, I provide the vertically disposed baffle plate 48 in the liquid inlet portion 11 of the valve casing, said baffle plate extending across the entrance to the valve chamber immediately in the rear 80 of the entrance to the by-pass 44, thus permitting an unobstructed flow of water through the latter to lift the piston when the hand controlled valve 41 is open.

85 I claim as my invention:

90 1. A device of the class described comprising a valve casing having inlet and outlet openings, a valve seated in said casing normally closing said outlet opening, a piston in the casing, a hollow stem upon the piston, a pin fixed upon the casing and projecting loosely into said stem and substantially closing the opening therein, an abutment upon the stem adapted after the piston has been moved a predetermined distance to engage and unseat said valve, an extension upon the casing having a passage-way leading from said inlet opening to one side of said piston, and a manually controlled valve normally closing said passage-way which when opened will permit the flow of liquid therethrough to actuate said piston.

95 2. A device of the class described comprising a valve casing having inlet and outlet openings, a valve seated in said casing normally closing the outlet opening and having a recess formed therein, a piston in the casing, a hollow stem upon the piston loosely projecting into said recess and substantially closing the same, a pin projecting into and substantially closing said stem, an abutment upon the stem spaced from the valve and adapted to engage and unseat the same after the piston has moved 100 a predetermined distance, an extension upon the casing having a passage-way leading from said inlet opening to one side of said piston and a manually controlled valve normally closing said passage-way which when opened will permit the flow of liquid therethrough to move said piston and cause the abutment on the stem to engage and unseat the first 105 mentioned valve.

110 3. A device of the class described com-

prising a valve casing having inlet and outlet openings, a valve seated in said casing normally closing said outlet opening; a piston in the casing, a hollow stem upon the 5 piston having a portion normally spaced from the valve and arranged when the piston is moved a predetermined distance to engage and unseat the valve, a tapered pin adjustable in the hollow stem and substantially 10 closing the opening therein, an extension upon the casing having a passage-way leading from said inlet opening to one side of said piston, and a valve normally closing said passage-way which when 15 opened will permit liquid to flow therethrough to actuate said piston.

4. A device of the class described comprising a valve casing having inlet and outlet openings, a valve seated in said casing 20 normally closing said outlet opening, a piston in the casing having an upstanding member thereon, said piston and upstanding member being provided with a restricted opening therethrough in communication 25 with the outlet opening of the valve casing, said upstanding member being adapted to when moved a predetermined distance to engage and unseat the valve, an extension upon the casing having a passage-way leading 30 from said inlet opening to one side of said piston and communicating with said restricted opening, and a manually controlled valve normally closing said passage-way, which when opened will permit liquid 35 to be discharged therethrough to move said piston and said upstanding member into engagement with the valve to unseat the same.

5. A device of the class described comprising a valve casing having inlet and outlet openings, a valve seated in said casing normally closing said outlet opening and having a pocket therein, a depending extension upon the valve provided with a 40 flange adapted to deflect the liquid discharged into the outlet opening when the valve is unseated, a piston in the casing, a member thereon extending into and substantially closing the pocket and serving to 45 unseat said valve when said piston is moved a predetermined amount in the direction of the valve, an extension upon the casing having a passage-way leading from said inlet opening to the lower side of said piston, 50 and a manually controlled valve normally closing said passage-way.

6. A device of the class described comprising a valve casing having inlet and outlet openings, a valve seated in said casing 60 normally closing said outlet opening and provided with a recess therein, a piston in said casing beneath said valve, a hollow stem upon the piston projecting into said recess, a tapered pin adjustable upon said 65 casing and projecting through said piston

and into said hollow stem, an abutment upon the stem adapted to engage and lift said valve after the piston has moved a predetermined distance, an extension upon the casing having a passage-way leading 70 from the inlet opening to the bottom of the piston, and a manually closed valve normally closing said passage-way.

7. A device of the class described comprising a valve casing having inlet and outlet openings and removable closures at its opposite ends, a partition within the casing forming a valve seat intermediate the inlet and outlet openings, a recessed valve upon said seat having an extension 80 adapted to strike one of said closures to limit the movement of the valve when opened, a piston within the casing beneath the valve having a hollow stem projecting loosely into the recessed portion of said valve, a tapered pin fixed upon the casing and extending through the piston and into said hollow stem, said stem being adapted to engage and raise said valve after the piston has been moved a predetermined distance, the opening in said stem and the recess in said valve forming a pocket having a restricted outlet for the fluid, thereby providing a cushion for the valve when returning to closed position, a by-pass leading 95 from the inlet chamber to a point beneath the piston and a manually actuated valve for controlling said by-pass.

8. A device of the class described comprising a valve casing provided intermediate its ends with a valve seat and with inlet and outlet openings above and below said seat, said ends being sealed with upper and lower closures, a valve upon said seat having a longitudinal recess therein 100 closed at its upper end and an extension projecting in proximity to said upper closure which serves to limit the upward movement of the valve, a piston beneath said valve having a hollow stem projecting 105 loosely into the recess within the valve, said stem having an abutment adapted to engage and raise the valve after the piston has been moved a predetermined distance, a tapered pin fixed upon the lower closure 110 and extending through the piston and into said hollow stem, a passage-way leading through the wall of the casing to a point between said piston and said lower closure and a valve for controlling said passage-way.

9. In a device of the class described, the combination of a valve casing provided with inlet and outlet compartments, a recessed valve normally cutting off communication between said compartments, a piston having a hollow stem projecting into the recess of the valve and forming therewith a cushioning chamber, a liquid inlet passage-way adapted to communicate with the 130

piston and said cushioning chamber and means for opening and closing said passage-way.

10. In a device of the class described, the combination of a valve casing provided with inlet and outlet compartments, a valve normally cutting off communication between said compartments, a piston movable relatively to the valve, means forming a liquid holding chamber between the valve and piston for cushioning the same, said chamber being varied in size by relative movement between the piston and valve, a passage-way for supplying liquid to said piston and said liquid holding chamber and means for controlling said passage-way.

11. In a device of the class described, the

combination of a valve casing provided with inlet and outlet compartments, a valve normally cutting off communication between said compartments, a piston movable relatively to the valve and having a member coöperating with the valve to form a liquid holding chamber provided with a restricted outlet, said chamber being variable in size by relative movement between the piston and valve, a liquid inlet passage-way leading to the piston and to said chamber, said piston when moved a predetermined distance being adapted to effect movement of said valve and means controlling said passage-way.

DANIEL M. McLAUGHLIN.
